UNITED STATES PATENT OFFICE.

ROLLA O. MILLS, OF REDONDO, WASHINGTON.

COMBINATION BATH-ROOM FIXTURE.

1,143,128.

Specification of Letters Patent. Patented June 15, 1915.

Application filed July 29, 1912, Serial No. 712,203. Renewed November 7, 1914. Serial No. 870,933.

To all whom it may concern:

Be it known that I, ROLLA O. MILLS, a citizen of the United States, and resident of Redondo, King county, Washington, have 5 invented certain new and useful Improvements in Combination Bath-Room Fixtures, of which the following is a specification.

My invention relates to bath room fixtures and consists of a combined bath tub, toilet 10 and wash bowls.

The object of my invention is to provide in a structure which is substantially unitary, a bath tub, a toilet or closet bowl and a wash basin, this being done in such a manner as to 15 economize in space required and also in plumbing expense.

My invention comprises the novel parts and combinations of parts which will be hereinafter described and particularly pointed out in the claims.

In the drawings I have shown my invention embodied in the form which is now preferred by me.

Figure 1 is a longitudinal vertical section, 25 the plane of the section passing centrally through the wash bowl. Fig. 2 is a plan view. Fig. 3 is an end elevation and partial section, the section being through the wash bowl.

Except as herein otherwise described, the 30 body of the bath tub 1, may be of any desired or standard construction. It has combined therewith a wash bowl or lavatory bowl 2, which may also be of any construction which 35 will suitably combine with the other special parts of my invention.

The bowl herein shown is of a simple type and has its overflow 6 discharging directly 40 into the bath tub. This overflow might be made direct into the water closet bowl or latrine if desired. The waste discharge from the wash bowl is shown as extending from its bottom through a pipe 7 into the closet bowl.

The closet bowl may be of any suitable 45 construction, preference being given to such type as will flush well under a small head of water. This bowl 3 is placed at the same end of the bath tub as the wash bowl, the 50 two being placed alongside each other, each occupying substantially half the width of the bath tub.

The water for flushing the closet bowl 55 comes from or through the wash bowl, this being filled and then discharged through the pipe 7 into the closet bowl. The faucet

which supplies the wash bowl with water may be allowed to run at the same time the wash bowl is being discharged into the closet bowl. An ample supply of water for effective flushing may thus be obtained. 60

The water supply comes through pipes 51 and 52 to faucets 5 and 50, one being for the hot water and the other for the cold water. These faucets are located to discharge directly into the wash bowls, being mounted upon an extension wall or back 10, which is placed between the bowls and the tub. While I prefer to supply the fixture with this extension partition, its use is not essential. 65

The water is supplied to the bath tub through a valve 70 and nozzle 71, which are located in the pipe 7 which carries the discharge from the wash bowl. This valve 7 may be of any type adapted to discharge the 70 supply coming from the wash bowl either into the closet bowl or into the bath tub. 75

The bath tub extends under the wash bowl and slightly under the closet bowl, the desire being to utilize as much of the space as possible. To this end the walls of the bath tub are, in some places, common to the wash bowl and to the closet bowl. This forms a space 12 beneath these parts which are of ample size to accommodate the feet and serve to 80 materially lengthen the space available in the tub. While the closet bowl extends to the floor level, its base is of comparatively small size and is located in one corner. The lack of this space in the bath tub is no loss 85 90 as there is much surplus space at the foot end of the usual tub.

The overflow from the bath tub is located at 4 and the discharge from this is conveyed, by a short pipe 40 into the closet bowl. The 95 wash bowl is provided with the usual plug to retain water therein when using this bowl. The valve 70 would normally be set to discharge into the closet bowl. When it is desired to fill the bath tub, the valve 70 is 100 turned to shift the discharge into the bath tub and the faucets turned on. The water then runs through the wash bowl into the tub.

The tub is provided with the usual discharge opening, this being shown as located at 13, under the wash bowl. The sewer connection for the closet bowl is at 30. 105

Beneath the rounded sides of the wash bowl, at the two outer sides thereof, a ledge 110 11 may be provided which will form a convenient place for the reception of soap,

brushes and other accessories of a bath and toilet room.

What I claim as my invention and desire to secure by Letters Patent is:

- 5 1. A toilet or bath room fixture comprising a bath tub having the upper portion of its walls at each side of and adjacent one corner recessed inward to form a seat recess extending substantially half way across the 10 tub end, and a closet bowl within the outlines of and beneath said recess having its inner walls combined with the walls of the tub.
- 15 2. A toilet or bath room fixture comprising a bath tub having the upper portion of its walls at each side of and adjacent one corner recessed inward to form a seat recess extending substantially half way across the tub end, a closet bowl beneath said recess 20 and having its inner walls combined with the walls of the tub and a wash bowl located above the tub and extending over the recess between said seat recess and the opposite side wall of the tub.
- 25 3. A toilet or bath room fixture comprising a bath tub having the upper part of its walls at each side of and adjacent one corner recessed inward to form a seat recess extending substantially half way across the tub 30 end, a closet bowl beneath said recess and having its walls combined with those of the tub, a wash bowl located over and extending across the space between said closet bowl and the opposite side wall of the tub a water 35 supply connection adapted to discharge into the wash bowl, and means for discharging the water from the wash bowl optionally into either the closet bowl or into the bath tub.
- 40 4. A toilet or bath room fixture comprising a bath tub having the upper portion of its walls at each side of and adjacent one corner recessed inward to form a seat recess extending substantially half way across the 45 tub end, a closet bowl formed integrally with the tub and occupying the space beneath said recess, a wash bowl located at an elevation above that of the closet bowl and

extending across the space between said closet bowl and the opposite side of the tub, 50 means for discharging water into said wash bowl, and means for discharging water from said wash bowl optionally into either the closet bowl or into the bath tub.

5. A toilet or bath room fixture comprising a bath tub having the upper portion of its walls at each side of and adjacent one corner recessed inward to form a seat recess, extending substantially half way across the tub end, a closet bowl within the space beneath said recess, said closet bowl being combined with the walls of the bath tub to form a continuous wall for the latter, a wash bowl located above the bath tub and extending across the space between the closet bowl and the opposite side wall of the bath tub, means for discharging the water from the wash bowl into the closet bowl, and a back or partition between said bowls and the tub and extending to a higher level than the 70 wash bowl.

6. A toilet and bath room fixture comprising a unitary structure containing a bath tub, a closet bowl located at one corner of the tub, a wash bowl located at an adjacent corner and at a higher level, the tub space extending under and against said bowls, said fixture being provided with a ledge beneath the exterior margins of the wash bowl adapted to receive small articles, an overflow connection for the tub located in the corner of the closet bowl next the wash bowl and connected with the closet bowl, a discharge connection from the wash bowl to the closet bowl adapted by its discharge to 85 flush the latter, an overflow from the wash bowl to the tub, and means for diverting the discharge from the wash bowl to the bath tub when desired.

In testimony whereof I have hereunto 90 affixed my signature at Seattle, Washington, this 19th day of July, 1912.

ROLLA O. MILLS.
